ALBERT ISLIKER, OF GENEVA, SWITZERLAND, ASSIGNOR OF ONE-HALF TO THE FIRM OF MOTOSACOCHE SOCIETE ANONYME, OF GENEVA, SWITZERLAND.

CONNECTING-ROD FOR PISTON ENGINES OR MACHINES.

1,295,091.

Specification of Letters Patent.

Patented Feb. 18, 1919.

Application filed August 7, 1918. Serial No. 248,725.

To all whom it may concern:

Be it known that I, ALBERT ISLIKER, engineer, a citizen of Switzerland, residing at Geneva, Canton of Geneva, in the Federation of Switzerland, have invented certain new and useful Improvements in and Relating to Connecting-Rods for Piston Engines or Machines, of which the following is a specification.

10 The present invention relates to the lubrication of connecting-rod heads and crank pins of piston engines or other machines.

In carrying out my invention the bushing in the head of the rod is provided on both 15 sides of the middle transverse plane with collecting devices for the lubricant after having served its purpose, said devices being in communication with other devices wherefrom the lubricant is discharged in a predetermined direction and in a predetermined position because of the forces imparted to it by the movement of the head.

In the drawing:

Figures 1 and 2 are partial sections of one 20 form of the invention, one section being taken parallel to the engine shaft, and the other at right angles thereto.

Fig. 3 is a diagrammatic section illustrating the operation of this form of the invention.

30 Fig. 4 is a partial section of another form of the invention.

Fig. 5 is a partial section showing a modification of the form illustrated in Fig. 4.

35 Figs. 6 and 7 are partial sections of still other forms of the invention, and

Fig. 8 is a partial section of a modification of the form shown in Fig. 7.

40 As shown in Figs. 1 and 2, the connecting-rod α is part of an internal combustion engine having one or more cylinders. In this structure the crank pit γ incloses the tight chambers b which constitute the pump chambers where the explosive mixture for

45 driving the engine is compressed by the corresponding piston which is connected by the rod α to one of the crank-pins e^1 of the crank-shaft e . The explosive mixture is admitted to a chamber b through its port q .

50 Now under these circumstances if the head of the connecting-rod α^1 is sufficiently lubricated, the oil after having accomplished its lubrication will work to the outside of this head α^1 and will be thrown in all directions, owing to the moving crank-pin e^1 , if nothing

is provided to prevent such action. The oil will therefore be thrown toward port q and when the compressed explosive mixture is conveyed through the port q to the cylinder it will carry with it a certain quantity of oil.

To prevent this oil waste, a bushing α^2 is placed in the revolving head of connecting-rod α^1 and is provided near each of its extremities with an inner annular groove α^3 , α^4 . The groove α^3 is shown as located, in a plane at right angles to the longitudinal axis of the bushing, and the groove α^4 in a plane at an inclination thereto. In the latter case there is less risk of marking the crank-pin, owing to the wear at the same place. Each of these grooves communicates through an orifice with a radially set pipe α^6 which is fixed at an acute angle to the axis of the connecting rod α and terminates on the outside of the head α^1 , in the under part of which said pipe α^6 is secured.

The operation of this form of the invention may be explained by reference to Fig. 3, which is a section taken vertically on the axis of the crank pin e^1 and passing through the groove α^3 , the dimensions of groove and oil being greatly exaggerated.

The oil is supplied to the head α^1 of the connecting-rod α in any suitable manner and after having lubricated the same, is collected in the grooves α^3 , α^4 . Owing to the movement of the head α^1 the oil in the grooves is acted upon by two forces. The one, a centrifugal force causes the oil in the grooves α^3 and α^4 during the revolution of shaft e , to always take a position which is opposite that of shaft e with regard to the axis of the crank-pin e^1 . This is shown in Fig. 3 for the four positions I, II, III, IV of the crank-pin.

The second force is inertia which acts materially in extreme positions of the piston, that is in the positions I and III of the crank-pin in Fig. 3. As the crank-pin approaches these two positions, I and III, its movement is retarded both upwards and downwards, until it ceases to move in a vertical direction, and then starts again downward or upward with a marked throw which the oil owing to the inertia can not follow at once. From the action of these two forces and from the position in which the pipe α^6 is fixed, it will follow that the oil can escape from the grooves α^3 , α^4 only in

the position III of the head, that is in a pre-determined direction and position so that the oil can not get near the orifice of port g . Thus the quantity of oil carried along by the 5 explosive mixture is so very small as to be negligible. At the time the oil escapes the gases in the crank case will be nearly at rest, which still further diminishes the risk of any oil being carried into the port g .

10 The pipe from which the oil escapes may be located at any desired position instead of being located at x^6 .

In the second form of the invention shown in Fig. 4 the annular grooves x^7 are placed 15 in the face-ends of the bushing x^2 , are open toward said faces, and are inclined with regard to said faces in such a way that the base of each groove is at greater distance from the axis of the bushing than its opening. These grooves are likewise provided with escape pipes like the pipes x^6 .

As shown in Fig. 5, the devices communicating with the oil-collecting grooves are pointed tongues x^8 made on the outside 25 of head x^1 and so formed as to cause the collected oil to be projected in a predetermined direction at the very moment of the throw of the crank occurring during the return stroke of the piston. The bushing may 30 be provided with these projecting tongues x^8 instead of making them on the head itself.

Referring to Fig. 6, it will be seen that the crank-pin e^1 gets its lubricating oil from a collecting-gutter 10 surrounding the bearing 35 11 of the shaft e by means of a channel e^{13} . At each end of the bushing x^2 the crank-pin e^1 has an annular projection e^{12} on which the oil is collected after having accomplished its lubricating action, and 40 from which it flows by the effect of centrifugal force into an inner annular groove x^9 on the bushing. The grooves x^9 communicate with the pipes x^6 .

The oil may also be forced under pressure 45 to the crank-pin through a canal e^{14} (Fig. 6) made in the crank and fed from a groove in the inside of the bushing in the bearing 12 or the shaft e . This delivery of the oil by pressure is advantageous especially if the oil is used to lubricate and also to cool the bushings of the crank and the bushing x^2 of head x^1 .

In another form of the invention as shown 50 in Fig. 7, the grooves x^8 are placed in the bushings x^2 at the corners where the crank-pin e^1 is rounded off, so as to join the arms of the crank. Each of these grooves x^8 is fitted with its own pipe x^6 . Fig. 8 shows a modification of this form of the invention.

60 Two grooves x^8 communicate with each other by means of a channel x^{13} made within the outer surface of the bushing x^2 and by means of said channel with the pipe x^6 .

The walls of the crank case g may be arranged, so as to collect or to retain the oil

which escapes from the projections or pipes on the head of the connecting-rod.

While I have described my invention as particularly applicable to an internal combustion engine it will be readily understood 70 that it is not limited to such use, and furthermore the escape pipes for the oil may be placed at substantially 90° from the positions shown and described so as to utilize the action of the centrifugal force only instead of both forces as described without departing from the nature and spirit of the invention.

I claim as my invention:

1. An apparatus of the class described, 80 comprising a crank shaft, a connecting rod, a bushing in the head of the connecting rod surrounding a crank pin on the crank shaft, the said bushing being adapted to collect the spent lubricating oil supplied between the 85 same and the crank pin, and an outlet connection so placed in its relationship to the bushing and crank pin as to discharge the collected lubricating oil at a predetermined point in the revolution of the crank shaft. 90

2. An apparatus of the class described, comprising a crank shaft, a connecting rod, a bushing in the head of the connecting rod surrounding a crank pin on the crank shaft and having a groove therein adapted to collect the spent lubricating oil supplied to the bushing and crank pin, and an outlet connection so placed and fixed in its relationship to the said bushing and crank pin as to discharge the lubricating oil collected in 100 the said groove at a predetermined position and in a predetermined direction in the revolution of the crank shaft. 95

3. An apparatus of the class described, comprising a crank-shaft, a connecting-rod, 105 a bushing in the head of the connecting-rod surrounding the crank-pin on the crank-shaft, and having a groove for collecting the lubricating oil, and an outlet connection for discharging the lubricating oil in a predetermined direction and at a predetermined point in the revolution of the crank-shaft. 110

4. An apparatus of the class described, comprising a crank-shaft, a connecting-rod, a bushing in the head of the connecting-rod 115 surrounding the crank-pin on the crank-shaft, and having a groove for collecting the lubricating oil, and a pipe extending through the head of the connecting rod and communicating with the groove in the bushing so as to discharge the collected lubricating oil in a predetermined direction and at a predetermined point in the revolution of the crank-shaft. 120

5. An apparatus of the class described, 125 comprising a crank-shaft, a connecting-rod, a bushing in the head of the connecting-rod surrounding a crank-pin in the crank-shaft and having a circumferential groove for collecting the lubricating oil, and a pipe 130

fixed in the head of the connecting-rod in a radial position and at an angle to the axis of the rod and communicating with the said groove in the bushing so as to discharge the lubricating oil in a predetermined direction and at a predetermined point in the revolution of the crank-shaft.

In testimony whereof I have affixed my signature in presence of two witnesses.

ALBERT ISLIKER.
